Des. 227,110
Patented June 5, 1973

227,110

PORTABLE AIRPLANE FLIGHT SIMULATOR TRAINER

Harry E. Cramer and Steven F. Cramer, both of
7609 S. Laurel St., Seattle, Wash. 98178

Filed Dec. 8, 1971, Ser. No. 206,243

Term of patent 14 years

Int. Cl. D19—07

U.S. Cl. D25—1 R

Fig. 1.

Fig. 2.

Fig. 4.

Fig. 3.

FIG. 1 is a top perspective view of a portable trainer showing our new design.

FIG. 2 is a top plan view thereof.

FIG. 3 is a side elevational view thereof.

FIG. 4 is an end elevational view thereof.

FIG. 5 is a top perspective view of the portable trainer of FIG. 1 showing an interior portion of our design.

FIG. 6 is a top plan view thereof.

FIG. 7 is a front elevational view thereof.

FIG. 8 is an end elevational view taken from the left of FIG. 5.

We claim:

The ornamental design for a portable airplane flight simulator trainer, substantially as shown and described.
